(57) **CLAIM**

The ornamental design for a light-emitting element module as shown and described.

DESCRIPTION

FIG. 1 is a front view of a light-emitting element module of the present invention;

FIG. 2 is a rear view thereof;

FIG. 3 is a top plan view thereof;

FIG. 4 is a bottom plan view thereof;

FIG. 5 is a right side view thereof;

FIG. 6 is a left side view thereof;

FIG. 7 is a front, top and right side perspective view thereof;

FIG. 8 is a rear, bottom and left side perspective view thereof;

FIG. 9 is a sectional view thereof with inner mechanism is omitted taken along the line 9-9 in FIG. 3;

FIG. 10 is an enlarged view thereof defined by the line 10-10 in FIG. 7; and,

FIG. 11 is an enlarged sectional view thereof with inner mechanism is omitted defined by the line 11-11 in FIG. 9. The broken lines show portions of a light-emitting element module that form no part of the claimed design.

The alternate long and short dash lines are merely the boundary lines between the claimed parts and the non-claimed parts.
